Primary Examiner — John Windmuller*Assistant Examiner* — John R Yeh(74) *Attorney, Agent, or Firm* — Robert J. Myers**CLAIM**

The ornamental design for an adjustable P clamp, as shown and described.

DESCRIPTION

FIG. 1 is a perspective view of our design for an adjustable P clamp;

FIG. 2 is a front elevation view thereof;

FIG. 3 is a back elevation view thereof;

FIG. 4 is a top plan view thereof;

FIG. 5 is a bottom plan view thereof;

FIG. 6 is a left elevation view thereof; and,

FIG. 7 is a right elevation view thereof.

The broken lines illustrate portions of the adjustable P-clamp that form no part of the claimed design.

Portions of the adjustable P clamp are shown broken away to indicate that these portions have no particular length beyond what is shown.
